SUPPORT STRAP FOR ELECTRON GUN STRUCTURES

George L. Case, Phoenix, N.Y., assignor to General Electric Company, a corporation of New York

Application September 12, 1955, Serial No. 533,622

5 Claims. (Cl. 313—82)

This invention relates to cathode ray tubes, and more particularly, to support straps for the electron gun structure of such cathode ray tubes.

Electron gun structures for cathode ray tube assemblies have conventionally employed insulative support rods disposed in parallel spaced relation to support the aligned array of tubular electrode elements which control the electron beam. The individual electrode elements have been separately connected to the support rods by means of strap members, usually having a central portion conforming circumferentially to the electrode elements, affixed to said element, and having terminal portions adapted to be secured to the support rods.

Prior known arrangements have proposed to insert the straps attached to the electrode elements into glass support rods thus securing said elements. Each strap is generally formed with a semi-cylindrical body portion adapted to be fitted to each cylindrical electrode element and having lateral portions which are in diametrically opposed relation. The terminal portions of the strap which are inserted into the molten glass material are merely straight extensions of the lateral portions. Because the lateral and terminal portions are on opposing ends of a straight-line it has heretofore been found necessary to accomplish the embedding process sequentially, or alternatively to maintain the electrode elements stationary while cradles containing the molten glass are brought into contact with the terminal portions.

Usual practice has been to attach the straps to the individual electrode elements by spot welding. The ends of the straps are then embedded in the support rods positioning the individual elements in spaced relation. A conventional method of embedding each of the straps into the rods, or beading, as this means of anchoring the straps is termed, consists in placing the entire unit of electrode elements in a jig and moving the jig such that common ends of the attached straps are inserted into a support rod while the latter is in a molten state, and then allowing the rod to cool; thereby anchoring the straps in the rod. The unit is next withdrawn, rotated, and the other common ends of the straps are inserted into their respective rod. This latter rod is allowed to cool, and the unit is withdrawn. The steps are repeated if additional supporting members are to be beaded. The just-described method has an inherent disadvantage in that, the beading operations are necessarily performed sequentially. Hence, the operation is time consuming and thus costly. A second disadvantage is that axial misalignment results, unless extreme care is exercised due to the unsymmetrical heating and cooling of the straps and of the support rods. In guns having multiple axes, a third disadvantage is that tilting of the axes of the electrode elements with respect to each other may result due also to the unsymmetrical heating and cooling.

Another conventional method for embedding the straps in the rods consists in moving the beading material into

2

contact with the ends of the straps while the electrode elements are held stationary. Because the various cradles holding the molten glass must be moved into contact with the end portions of the straps, the machine employed to perform the operation is complicated, unwieldy, and expensive.

Accordingly, it is a principal object of my invention to provide a new and improved support strap for a cathode ray tube gun structure that is expeditiously and efficiently affixed to the support rods resulting in considerable cost and time saving in the manufacture of such structure.

Another object of my invention is to provide a new and improved support strap that accurately maintains the electrode elements in predetermined axial alignment.

Another object of my invention is to provide a new and improved support strap that permits simultaneous beading.

Further objects and advantages of my invention will become apparent from the following description and the features of novelty which characterize my invention will be pointed out with particularity in the claims annexed to and forming part of this specification.

In carrying out the objects of my invention I provide a novel strap support for use in electron gun structures for cathode ray tubes, said strap supports having terminal portions disposed in the same general direction from a common plane such that beading of all terminal portions can be accomplished simply, efficiently, and simultaneously.

For a detailed explanation of my invention, reference is made to the accompanying drawings in which:

Figure 1 is an elevational view of a cathode ray tube gun structure embodying features of my invention;

Figure 2 is an isometric view of the lower portion of the gun structure of Figure 1;

Figure 3 is a cross sectional view taken along the line 3—3 of Figure 2;

Figure 4 is an isometric view of a strap constructed according to my invention and shown in Figures 1-3;

Figure 5 is a cross sectional view of a modified embodiment of my invention shown mounted on a cylindrical element; and

Figure 6 is a cross sectional view of another modification of my invention, also shown mounted in a cylindrical element.

In Figure 1, an electron gun is shown located in the neck portion 11 of a cathode ray tube envelope; said electron gun comprising a cathode-control grid electrode assembly 12, a number two or screen grid 13, an anode or number 3 grid 14, and a magnetic focusing means generally indicated at 15. Each of the preceding elements or assemblies may be of any suitable conventional design and for purposes well known to those skilled in the art. Since the cathode element is not, per se, a part of the invention it is included in the drawing generally as part of electrode assembly 12. Lead wires connecting the elements 12, 13, and 14 to the closed end of the neck portion 11 are not shown since the arrangements therefore and the manner of connection are well known to those skilled in the art, and, per se, form no part of the invention. Spacer clips 16 of any suitable conventional type can be used to maintain the gun assembly in proper spaced relation to the wall of the neck portion 11, as is also well known in the art.

While the present invention is described in association with a magnetic focus type of gun structure, it will be understood that it is not limited to this particular type of gun it being clear that electrode elements similar to those illustrated at 12, 13, and 14, or the equivalent, are commonly employed in electrostatic focused guns of the so-called bent-gun, tilted-straight gun, and the other types.

For maintaining the electrode elements, 12, 13, and 14 in spaced alignment one or more insulative glass rods or beads 17, 18 are provided in adjacent spaced relation to said elements. As shown more clearly in Figure 2, the cathode-control grid assembly 12, the screen grid 13, and the anode 14 are connected to the glass beads 17, 18 by means of support or beading straps 21, 22, 23, and 24 respectively, constructed and arranged in accordance with the preferred embodiment of the present invention. The beading straps 21, 22, 23 and 24 may be similarly 10 constructed and may be formed generally, as shown clearly in Figure 4, of any suitable materials and in any suitable manner as by bending or stamping to provide; a semicylindrical body portion 25, lateral portions 26 which extend from the chordally opposed ends of the body portion 25, and terminal portions 27 which are bent to define an angle with said lateral portions 26.

The terminal portions 27 are formed such as to extend in the same direction and substantially parallel to one another. In the preferred embodiment shown clearly in Figures 2 and 4, the terminal portions 27 are formed at approximately right angles to the co-planar lateral portions 26. By this construction, the apexes 28 of the terminal portions 27, are inserted perpendicularly into the molten glass beads 17 and 18, thus effecting little distortion of the beads 17 and 18. This allows the molten glass to flow quickly and evenly to embed each of the terminal portions 27, anchoring them securely to the respective beads 17 and 18. The terminal portions 27 must be of sufficient length to provide a good anchoring surface. I have found for best results that the terminal portions 27 should preferably project into the beads 17 and 18 approximately $\frac{1}{8}$ " as a minimum. It is desirable that the apexes 28 be inserted into the bead material by a force which is parallel to the terminal portions 27, thus placing less tension on each strap as it is inserted into the bead material and consequently minimizing the possibility of axial misalignment.

In assembly, the straps 21, 22, 23, and 24 are initially affixed to the individual electrode elements 12, 13, and 14 as by spot welding. Due to the special construction all of the terminal portions 27 of the straps 21, 22, 23, and 24 project in the same general direction. In the interest of practical manufacturing techniques the terminal portions 27 are affixed so as to project downward. The electrode elements 12, 13, and 14 with the respectively affixed straps 21, 22, 23, and 24 are placed in a jig to hold elements 12, 13 and 14 in fixed spaced relation. Cradles adapted to hold the glass beads 17 and 18 are disposed in spaced relation beneath the straps. After a bead of glass is melted in the cradles the jig is moved toward the cradles, simultaneously forcing all the apexes 28 of the terminal portions 27 into the molten glass. The glass is allowed to cool thereby anchoring the straps 21, 22, 23, and 24, and the now fixedly spaced electrode elements are withdrawn.

With relation to a common chordal plane through each of the cylindrical electrode elements 12, 13, and 14, each strap is fitted on that same side of the cylinder as the terminal portions extend, as indicated in Figure 3. This construction is preferred since as the terminal portions 27 of each strap is forced into the molten beads 17, and 18, each strap is pressed against the electrode element to which it is attached and no tension is placed on the spot welds, and a minimum tension is placed on the straps 21, 22, 23, and 24. If the strap is fitted on the opposite side of the cylindrical element as shown in Figure 5 the force exerted on each strap is also placed on the spot welds necessitating that the welds and the straps be of stronger construction. Although the first design is preferred, the second design has been successfully employed.

If additional supports are required, strap members may be placed in circumferential spaced relation as for example in Figure 6. By this construction, a support member 31 may be simply a straight extension designed to

extend in the same direction as the terminal portions 27 of the associated straps. Likewise, extra support members can be added to the embodiment shown in Figure 5; the terminal portions of each additional support member being formed to extend in the same direction.

It will be understood that the body portion 25 need not conform to the contour of the associated electrode element, the lateral portions then being connected directly to spaced points on the associated electrode element as by spot welding.

Also, it will be understood that such lateral portions may be formed integrally with the associated electrode element as for example by striking out portions of the cylinder wall to form such lateral portions.

It will further be understood that while glass beads or rods where described hereinabove, rods of other insulative material can be similarly employed such as quartz, mica, ceramic or the like as a base for anchoring the electrode elements of the gun structure.

Although the present invention has been illustrated by specific examples, it will be obvious to those skilled in the art that modifications may be made without departing from the spirit thereof.

What I claim as new and desire to secure by Letters 25 Patent of the United States is:

1. A strap for supporting an electrode in an electron discharge device comprising a body portion adapted to be secured to the electrode, arm portions attached to said body portion and extending outward from said body portion in opposite directions, a terminal portion on each respective arm portion adapted to be embedded in respective heat-softenable support rod, all of said terminal portions extending in the same direction whereby through displacement of said strap in said same direction all of said terminal portions can be embedded simultaneously.

2. A strap for supporting a cylindrical electrode between a plurality of heat-softenable supports in an electron discharge device comprising a body portion having a cylindrical curvature adapted to complement the electrode, and a plurality of terminal portions spaced according to the spacing of said supports and each adapted to be embedded in a respective support, all of said terminal portions extending toward their distal ends in substantially the same direction as that in which the convex surface of said body portion faces, whereby through displacement of said strap in said common direction relative to said supports all of said terminal portions can be embedded simultaneously.

3. In an electron discharge device, an electrode, a plurality of heat softenable spaced support members between which the electrode is located, respective connectors secured to said electrode opposite said respective support members and having terminal portions remote from said electrode embedded in said respective support members, said terminal portions all extending toward their extremities in a common direction to enable simultaneous embedding thereof by simultaneous displacement of said terminal portions in said common direction relative to said support members.

4. In an electron discharge device, an electrode, a plurality of spaced support rods of heat-softenable material, strap means attached to said electrode for supporting said electrode from said rods, said strap means having arm portions extending laterally outwardly from said electrode in opposite directions, and a terminal portion on each arm portion embedded in a respective support rod, said terminal portions extending in the same direction and approximately perpendicular to the plane of said arm portions.

5. In an electron discharge device, a cylindrical electrode, a plurality of spaced support members of heat-softenable material, a support strap for said electrode, said strap having a semi-cylindrical body portion to the concave surface of which said electrode is attached, arm portions extending outwardly from said body portion,

and a terminal portion on each arm portion embedded in a respective support member, said terminal portions extending toward their distal ends in substantially the same direction as that in which the convex surface of said body portion faces, whereby said terminal portions may be embedded simultaneously by simultaneous displacement thereof relative to said support members in said same direction.
